WILLIAM L. MAPPES, OF CINCINNATI, OHIO, ASSIGNOR TO THE CORCORAN-BROWN LAMP COMPANY, OF CINCINNATI, OHIO, A CORPORATION OF OHIO

LAMP SOCKET HOLDING DEVICE

Application filed May 27, 1929. Serial No. 366,323.

This invention relates to an improved lamp socket holding device especially designed with an object of producing an effective and yet simple means by which automobile lamp bulbs will be held positively against displacement from the focal center of the lamp reflector.

A further object is to produce a simple and effective socket holding device which will be easy to manufacture, inexpensive, and require the simplest of installation operations without having to resort to the use of tools.

These and other objects are attained in the socket holding device described in the following specification and illustrated in the accompanying drawing, in which:

Fig. 1 is a side elevation, partially in section and illustrated fragmentally, showing a lamp bulb and connector mounted in a reflector equipped with the device embodying my invention.

Fig. 2 is a view upon enlarged scale, taken on the line 2—2 of Fig. 1, showing the improved device installed with relation to the connector mounted therein, with the reflector tube cooperating with the device to show the position of the cooperating parts.

In the usual automobile head lamp, reflectors are provided which, like the reflector 3, shown fragmentally in Fig. 1, contain the connector 4 which is mounted for reciprocation in a reflector tube 5 clinched in the axial opening of the reflector. This connector 4 provides the means by which the lamp bulb 6 is held with its filament in the approximate focal center of the reflector 3. However, some means must be provided to prevent displacement of the lamp bulb along the reflector axis, as well as to provide means to prevent vibration of the bulb which would cause apparent unsteadiness or flickering of the light beam projected by the lamp.

In my improved construction, I have in a most simple manner overcome these difficulties by providing but one element which will positively prevent axial movement of the connector and its mounted lamp bulb, as well as hold the bulb against any tendency to vibrate. This simple provision is made in the form of a substantially C-shaped spring

7 which clips around the reflector tube 5 for this purpose. At one end of the spring a pin 8 is riveted, while at the other end an inwardly bent finger 9 is provided, both ends 10 and 11 of the spring being turned outwardly 55 to permit it to be sprung over the reflector tube. When spring 7 is in position, as shown in Figs. 1 and 2, its pin 8 occupies holes 12 and 13 in the tube 5 and connector 4 respectively so that the connector is held against 60 both rotary movement and axial movement. With the pin in this position, finger 9 occupies a slot 14 in the reflector tube and bears upon the connector by extending therethrough. In this manner vibration of the 65 connector is prevented. Thus with but one simple agency the connector is in all respects held against movement so that the light source remains fixedly in the focal center of the reflector.

Disconnection is effected very easily by pulling upon end 11 to slip the spring from mounted position on the reflector tube, thus freeing all the parts.

Having thus described my invention, what I claim is:

A lamp socket holding device for automobile lamps, comprising in combination with a mounting tube and a connector mounted therein, a C-shaped spring mounted on the tube detachably by partial circumferential engagement therewith, and a pin on one end of the spring loosely engaging holes in the tube and the connector thereby locking the connector against rotary and axial movement 80 in the tube, the opposite end of the spring being bent toward the tube, said tube having an opening therein to receive the opposite end of the spring to permit of its bearing engagement with the wall of the connector, 85 the tips of the two ends of the spring being bent outwardly to facilitate removal and replacement of the spring on the tube.

In testimony whereof I hereunto affix my signature.

WILLIAM L. MAPPES.
